(57) CLAIM

I claim the ornamental design for a tablet, as shown and described.

DESCRIPTION

FIG. 1 is a perspective view of a tablet, showing our new design;

FIG. 2 is a side elevational view of FIG. 1; and

FIG. 3 is a top plan view of FIG. 1; and,

FIG. 4 is a bottom plan view of FIG. 1; and,
FIG. 5 is a cross sectional view taken along lines 5-5 of FIG. 3.

1 Claim, 3 Drawing Sheets

FIG. 1

FIG. 2

FIG. 3

FIG. 4

FIG. 5
